UNITED STATES PATENT OFFICE.

HOMER G. ELLIOTT, OF HICKSVILLE, OHIO.

LATHING-HAMMER.

SPECIFICATION forming part of Letters Patent No. 244,209, dated July 12, 1881.

Application filed December 18, 1880. (Model.)

To all whom it may concern:

Be it known that I, HOMER G. ELLIOTT, of Hicksville, in the county of Defiance and State of Ohio, have invented a new and valuable 5 Improvement in Lathing-Hammers; and I do hereby declare that the following is a full, clear, and exact description of the construction and operation of the same, reference being had to the annexed drawings, making a part of this 10 specification, and to the letters and figures of reference marked thereon.

Figure 1 of the drawings is a vertical section. Fig. 2 is a side view of a portion of the device. Fig. 3 is a detail view of the parts 15 arranged to be applied to the hatchet-head.

This invention relates to hammer-heads.

The invention consists in the construction hereinafter described.

In the drawings hereto annexed, A is a 20 hatchet having the angular head B. From this head rises a boss, C, whose periphery c is within the edges of head B, forming a shoulder, b. From this boss rises another and smaller one, D, forming a shoulder, d.

25 Projecting upward from boss D is a cylindrical bar, E, of less diameter than boss D, forming a shoulder, e, said bar having the hammer-point e', preferably magnetized.

F is a hollow cylinder, having a bore, f, of 30 the diameter of boss D, and two slots, f' f', extending from one end nearly to the other and on opposite sides.

G is a spiral spring, with a diameter large enough to permit its easily slipping on cylinder F.

35 H is a hollow cylinder, having an exterior diameter equal to that of the bore of cylinder F and a bore of a diameter equal to that of bar E. Near one end at opposite sides are 40 the lugs h h.

I is a hollow cylinder, having a bore of the diameter of boss C, terminated at the cap-flange k, having an orifice, k', of the diameter of exterior of cylinder H.

45 l is a screw-threaded orifice in cylinder I, and n a depression in boss C for a screw, K.

The relation in the lengths of the bosses, bar,

and cylinders is such that when the latter are in place without the spring, cylinder H rests on shoulder e, cylinder F on shoulder d, cylinder 50 I on shoulder b, the outer end of cylinder F bears against the inner face of cap-flange k, and the outer end of cylinder H projects through orifice k' nearly to the end of bar E, its lugs h resting in slots f' f'.

55 The hatchet, bosses, and bar are all made in one piece.

In putting the device together slotted cylinder H is slipped onto shoulder e, spring G over this, cylinder F inside cylinder H, its lugs 60 h h projecting through slots f' f' and bearing on spring G. Then cylinder I is slipped on and made fast by screw K. The spring G presses against cylinder H and forces it out until lugs h h strike cap-flange k, when the outer end, h², 65 of said cylinder will be somewhat beyond the end or point e' of bar E.

A device of this kind is specially adapted for use in lathing or in places where it is difficult or well nigh impossible to hold the nails. 70 A nail is placed in the cylinder H, which acts as a holder, the point of the nail protruding. A blow of the hammer causes the cylinder H to recede and the bar E to drive the nail at the desired point. This action of the spring 75 relieves to a great extent the shock on the arm, and the holder prevents springy material from throwing off the nail.

What I claim is—

In a lathing-hammer, the combination of the 80 bosses C and D and the bar E with the slotted hollow cylinder F f' f', hollow cylinder H, having lugs h h, spring G, and the hollow cylinder I, having orifice k', secured to the boss C, substantially as and for the purposes set 85 forth.

In testimony that I claim the above I have hereunto subscribed my name in the presence of two witnesses.

HOMER GENIO ELLIOTT.
